BUOYANT VEST

Edgar G. Baker, Carbondale, Pa., assignor to Gentex Corporation, New York, N.Y., a corporation of Delaware

Filed Jan. 8, 1962, Ser. No. 68,231

Term of patent 14 years

(Cl. D71—1)

I claim:

The ornamental design for a buoyant vest, substantially as shown and described.
